UNITED STATES PATENT OFFICE.

WILLIAM A. MORTON, OF PITTSBURGH, PENNSYLVANIA, ASSIGNOR TO THE AMSLER-MORTON COMPANY, OF PITTSBURGH, PENNSYLVANIA, A CORPORATION OF PENNSYLVANIA.

RECUPERATOR STRUCTURE FOR FURNACES.

Application filed October 9, 1922. Serial No. 593,195.

My invention consists in new and useful improvements in the structure of recuperative furnaces; and also in the tiles or structural elements which are used in the 5 construction of the same.

In such furnaces, as now constructed, the waste or heating gas passages in the recuperator are horizontal, and are formed or defined by means of horizontally disposed elements or tile.

These elements expand when heated, and, as they cool, their joints open, permitting the preheated air to be drawn into the chimney instead of being led to the furnace, and also 15 permitting the waste gases to leak into the air passages and to be returned to the furnace.

Furthermore the horizontally disposed elements are distorted by the heat, and are unable, as they cool, to resume their proper alignment, thus causing further leakage.

I have invented a new and improved recuperator structure wherein the air and waste gas passages are all vertical. Moreover such passages are formed by vertically disposed refractory elements or tile which interlock together, the weight of the superimposed elements insuring sealed joints at all times, whether the elements are heated or 30 cooled.

Thus, material leakage is impossible, and there can be no escape of the air into the waste gas flues nor of the waste gases into the air flues.

For use in my improved recuperator, I have invented new and improved flue elements or tile adapted to be assembled in vertically disposed stacks by interposed flange elements or tile, thus forming the vertical 40 air flues.

I have also invented new and improved interlocking flange elements or tile which are interposed in interlocking relation between the ends of the vertically aligned flue tile, and 45 which serve the four-fold purpose of supporting the air flues in place; forming self-sealing and self-maintaining joints in the air flues; properly spacing the air flues apart to form the intervening flues for the waste gases, and bracing the air flue tile so that they 50 at all times maintain their proper positions and alignment.

I have also devised new and improved ele-

ments or tile which form the top and bottom of the air flues, and which also form the top and bottom closures of the flues for the waste gases, thus preventing the admission of the latter to the air flues, such tile also serving to support and brace the ends of the air flues in proper positions and alignment.

Other novel features of construction and arrangement of parts will appear from the following description.

In the accompanying drawings which are, however, merely intended to be illustrative 65 of the principles of my invention without limiting the scope of the latter to the construction shown, Fig. 1 is a section, taken along the line I—I in Fig. 2, showing a recuperative furnace which embodies the principles of my invention, the furnace chamber being shown only in part; Fig. 2 is an irregular section of the same, taken along the lines II—II and III—III in Fig. 1; Fig. 3 is an enlarged detail view in plan showing 70 four air flues, the top tile and the top air flue tile being removed to show the flange tile; Fig. 4 is a similar view showing the top of said air flues with the top tile in place; Fig. 5 is a vertical section, taken along the line 75 V—V in Fig. 4, showing the assemblage of the various characters of tile to form the flues; Fig. 6 is an enlarged perspective showing one of the flange tile; Fig. 7 is an enlarged perspective showing one of the tile 80 which is used for either a base or a top tile; Fig. 8 is an enlarged perspective of the air flue tile, and Fig. 9 is a plan view showing a modified form of flange tile.

The following is a detailed description of 85 the drawings, reference being first had to Figs. 1 to 8, inclusive.

The general construction of the furnace as shown, and which forms no part of my present invention, is of a well known type comprising the furnace proper or heating chamber A having a hearth 1, in the rear of which is the recuperator chamber B in which the air is heated by means of the waste gases from the furnace, said gases being shown as led 90 rearwardly under the hearth through the horizontal flue 2; which flue connects at its rear end through the port or ports 3 with the chamber B somewhat below the top of the latter.

The upper end of the chamber B is con-

nected by the port or ports 4 with the combustion chamber C whence the heating flames pass into the top of the furnace chamber A through the port or ports 5.

5. The combustion chamber C may be supplied with producer gas through the vertical passage 6, or with oil or other fluid fuels through the burner ports 7 in the upper portion of the chamber.

10. The bottom of the recuperator chamber B is provided with a series of parallel and spaced apart partitions 8 which form between them the air inlet passages 9 connected at one side of the chamber B with the air

15. manifold D, and which partitions support the flue structure of the recuperator. 9^a shows individual sliding dampers for the air passages 9.

Above the tops of the partitions 8 the rear 20. wall of the chamber is provided with the port or ports 10 which connect with the chimney flue E for the escape of the waste gases which travel downwardly through the chamber B.

25. My improved recuperator or flue structure provides vertical air flues, through which the air passes upwardly; and, surrounding the air flues, vertical gas flues through which the waste gases pass, both air and gases traveling vertically through the recuperator.

I provide a novel and advantageous flue structure which is of the following character.

35. F represents the vertically disposed air flue tile, which are shown provided with internal longitudinal partitions 11 dividing the interior of the tile into two or more sub-flues. I have shown but one internal partition, but it will be understood that two or more may be provided, or the flue tile may be without partitions, if thought preferable. The ends of the partitions extend somewhat beyond the extremities of the tile, for a purpose to be described.

40. I have shown the tile of substantially rectangular cross section, but it will be understood that the same may be of cylindrical or other cross-sectional shape, if desired.

50. The ends of the vertically alined tile F are inserted into the flange tile G whose preferred form is illustrated in Fig. 6. Said flange tile have their internal bore of proper contour and dimensions to receive the upper and lower ends of the adjacent flue tile, a shoulder 12, intermediate of the bore of the flange tile, supporting the upper flue tile and resting upon the lower flue tile. The flange tile therefore connect and interlock 55 the flue tile together, the shoulders 12 being interposed between the ends of the alined flue tile, and the internal bore of the shoulder, being substantially the same as that of the flue tile. The protrusion of the partitions 11 from the ends of the flue tile is

sufficient to cause ends of the partitions of two vertically alined flue tile to abut, thus continuing the sub-flues through the flange tile. The insertion of the ends of the flue tile F into the bore of the flange tile G prevents leakage at the ends of the flue tile, and, also in case the flue tile become cracked or broken, the fragments are held in place, maintaining the flue structure.

70. The perimeters of the flange tile G are provided with horizontally disposed lugs 13, the lugs of each flange tile abutting and bearing against the lugs of the adjacent flange tile, thus bracing the air flues against lateral movement and spacing them apart 80 to form, between the air flues, and surrounding the same, vertical flues for the passage of the waste gases.

75. In Fig. 9 I show a modified form of flange tile G' which have but one spacing 85 and bracing lug 13^a on each side, the same being centrally disposed.

80. Each stack of vertically alined and interlocked flue tile is supported by one of the tile H, shown in Fig. 7, which tile H are 90 also used, in inverted position, as the top tile of the stacks.

85. The tile H are provided with a differential bore, the larger bore 14 being of sufficient size and proper dimension so that the 95 end of the flue tile F may be inserted therein, the degree of insertion being limited by the internal shoulder 15 in the bore of the tile H. The bodies of the tile H are solid and their perimetral contour preferably 100 rectangular, so as to fit together to fill and close the spaces between the air flues.

90. In constructing the recuperator, a floor composed of the tile H, with their larger 105 bores uppermost, is built over and supported by the partitions 8, and the lowermost flue tile of the air flues are stepped in said bores, being supported by the shoulders 15. The abutting edges of the tile H are provided with a tongue-and-groove engagement as shown at 16 and 17 in Fig. 7, so as 110 to form a tight floor for the recuperator about the air flues. Said tile H are also mounted on top of the air flues above the level of the waste gas ports 3, the larger 115 bores 14 of the tile H being in this case below and fitting over the flue tile F, the shoulders 15 of the tile H supporting the latter on the top of the air flues, and the abutting edges of the tile H interlocking to 120 form a tight floor for the recuperator about the tops of the air flues.

125. It is apparent from the foregoing that the waste gases will pass from the furnace chamber through the ports 3 into the interior of the recuperator chamber B, below the level of the floor formed by the top tile H, and will pass downwardly, through the waste gas flues surrounding the air flues, to the floor formed by the bottom tile H,

thence passing through the ports 10 to the chimney flue E.

Likewise, it is apparent that the air will enter from the manifold D into the air passages 9, and thence pass into the vertical air flues, and at the top of the same through the ports 4 into the combustion chamber C, the air being thoroughly heated during its passage through the air flues.

10 It is quite evident that the expansion of the tile, under the influence of the hot gases will not open the joints between the air flue tile and the flange tile, or between the air flue tile and the top and bottom tile H, and 15 it is likewise apparent that the contraction of the tile will not result in opening said joints, as the interlocked elements will automatically take up changes due to their expansion and contraction without leakage, 20 and the joints will remain automatically sealed. The weight of the recuperator structure acts to automatically take up expansion and contraction.

While it is usual to make the elements or tile of refractory clays, it is quite evident that steel or cast-iron, or any other material able to withstand the heat without rupture may be used.

In assembling the elements of the recuperator, the ends of the flue tile are lightly buttered with a clay mortar or other cementitious substance.

Although, for the sake of clearness in illustrating the principles of my invention, I have described in detail the embodiment of the same shown in the drawings, I do not limit myself thereby, but claim broadly:—

1. In a recuperator structure for furnaces, 40 the combination of a plurality of vertically disposed air flues, each flue being composed of a plurality of vertically disposed flue tile in superimposed relation, and horizontally disposed flange tile interposed between adjacent alined flue tile and socketed above and below to receive the ends of the flue tile, and said flange tile being provided with integral lateral projections, the projections of adjacent flange tile being in engagement 45 to brace the associated air flues against lateral displacement.

2. In a recuperator structure for furnaces, the combination of a plurality of vertically disposed air flues, each flue being composed 55 of a plurality of vertically disposed flue tile in superimposed relation, and horizontally disposed flange tile interposed between adjacent alined flue tile and socketed above and below to receive the ends of the flue tile, and 60 adjacent flange tile being provided with mutually engaged projecting portions for bracing the air flues against lateral displacement.

3. In a recuperator structure for furnaces, 65 the combination of a plurality of vertically

disposed air flues, each flue being composed of a plurality of vertically disposed flue tile in superimposed relation, and horizontally disposed flange tile interposed between adjacent alined flue tile and socketed above 70 and below to receive the ends of the flue tile, and said flange tile being provided with lateral corner projections which contact with similar projections on adjacent flange tile thereby bracing the air flues against lateral 75 displacement and providing passages between the adjacent flange tile for the passage of waste gases.

4. Flange tile for use in assembling vertically disposed flue tile to form a recuperator structure, having internal bores into which the ends of adjacent flue tiles are inserted, said bores having internal shoulders which are interposed between the ends of the flue tile, and said flange tile being provided with integral projections at the corners to contact with similar projections of adjacent flue tile whereby the flues are held against lateral displacement and vertical 85 passages are formed between adjacent air 90 flues for the passage of the waste gases.

5. For use in connecting the ends of vertically alined flue tile to form a flue, horizontal flange tile having a bore adapted to receive the ends of the flue tile and provided 105 with integral external projections at its corners adapted to engage the similar projections of the flange tile of adjacent flues to maintain the flues in proper spaced relation.

6. For use in connecting the ends of vertically alined flue tile to form a flue, flange tile having a bore adapted to receive the ends of the flue tile and said bore being provided intermediate of its ends with an internal shoulder which is interposed between the ends of the flue tile, and said flange tile being also provided with integral external projections at its corners adapted to engage the similar projections of the flange tile of adjacent flues to maintain the flues in spaced 110 relation.

7. The combination of a pair of alined flue tile to be connected together to form a flue, a flange tile interposed between said flue tile and having a bore in which the adjacent ends of said flue tile are inserted, said bore being provided intermediate of its ends with an internal shoulder which is interposed between the ends of the flue tile, and said flue tile being provided with longitudinally disposed partitions to form a plurality of flue passages, said partitions being extended beyond the end of the flue tile so as to abut together to continue the flue 115 passages through the flange tile.

8. An end tile, for use in forming the end of a recuperator composed of vertically disposed air flues formed of flue tile, said end tile being provided with a differential bore, 120 the larger diameter of which receives the end 125

- of the flue tile while the shoulder interposed between the bores bears against the ends of the flue tile.
9. An end tile, for use in forming the end of a recuperator composed of vertically disposed air flues formed of flue tile, said end tile being provided with a differential bore, the larger diameter of which receives the end of the flue tile while the shoulder interposed between the bores bears against the end of the flue tile, and the perimetral edges of the end tile being formed to engage the edges of adjacent end tile to form a closure between the air flues.
10. An end tile for use in forming the end of a recuperator structure and provided with a central opening to receive the end of the flue tile, and the perimeter of said end tile being provided with means for forming a tongue and groove engagement with adjacent end tile.
11. An end tile for use in forming the end of a recuperator structure and provided with a central opening to receive the end of the flue tile, said opening being also provided with an internal shoulder which engages the end of the flue tile, the perimeter of said end tile being provided with means for forming a tongue and groove engagement with adjacent end tile.
12. A recuperator structure for furnaces comprising a chamber, a pair of closures spaced apart in said chamber, said closures being comprised of end tile having abutting perimetral edges, and said end tiles being provided with openings having internal shoulders, air-flues extending between said closures and being comprised of flue tile assembled in alinement, the extremities of the flue tile forming the ends of the air-flues being inserted into said openings against said shoulders, flange tile interposed between alined flue tile to connect the same together, and means carried by said flange tile for holding said air-flues in proper alinement.
13. A recuperator structure for furnaces comprising a chamber, a pair of closures spaced apart in said chamber, said closures being composed of end tile having abutting perimetral edges, and said end tiles being provided with openings having internal shoulders, air-flues extending between said closures and being comprised of flue tile assembled in alinement, the extremities of the flue tile forming the ends of the air-flues being inserted into said openings against said shoulders, flange tile interposed between
- aligned flue tile to connect the same together, and lateral projections on said flange tile adapted to interengage to hold the air-flues in proper alinement.
14. A flue tile for the purpose described having an internal longitudinal partition which protrudes from the ends of the flue tile so that when said flue tiles are assembled with interposed flange tile, the ends of the partitions of adjacent flue tile impinge against each other, for the purpose described.
15. For use in connection with the flue tile for the purpose described, a flange tile having a socketed bore adapted to receive and engage the end of the flue tile, and having its perimetral edges adapted to interlock with those of adjacent flange tile to form a gas tight floor between the adjacent flues.
16. For use in connection with the flue tile for the purpose described, a flange tile having a bore into which the flue tile are inserted and said bore being provided with an internal shoulder against which the flue tile bear, said flange tile having its perimetral edges formed to interlock with those of adjacent flange tile to form a gas tight floor between the adjacent flues.
17. A recuperator comprising a chamber enclosed in vertical walls, a plurality of pipes extending longitudinally through the chamber and comprised of relatively short sections of hollow tile, transversely disposed centrally apertured blocks interposed between ends of each section having recesses therein into which the pipe sections fit, and spacing means on some of the blocks for holding them in position and providing intervening openings to allow gases to circulate between the blocks.
18. A recuperator comprising a chamber enclosed in vertical walls, a plurality of pipes extending longitudinally through the chamber and comprised of relatively short sections of hollow tile, blocks interposed between ends of each section having openings therethrough in alinement with the openings through the hollow tiles, said blocks serving to keep the pipe sections spaced on all sides from one another, and means on some of the blocks providing passageways for allowing gases to circulate longitudinally through the chamber around the pipes and between the blocks.

Signed at Pittsburgh, Pa. this 23rd day of Sept. 1922.

WILLIAM A. MORTON.
